UNITED STATES PATENT OFFICE.

WILLIAM J. ELDER, OF OSWEGO, NEW YORK, AND EDGAR A. ALLEN, OF CHICO, CALIFORNIA, ASSIGNORS TO THE DIAMOND MATCH COMPANY, OF CHICAGO, ILLINOIS, A CORPORATION OF ILLINOIS.

BLOCK-FEEDING MECHANISM FOR MATCH MACHINES.

Application filed June 3, 1922. Serial No. 565,742.

To all whom it may concern:

Be it known that we, WILLIAM J. ELDER, a resident of Oswego, in the county of Oswego and State of New York, and EDGAR A. ALLEN, a resident of Chico, in the county of Butte and State of California, both citizens of the United States, have invented certain new and useful Improvements in Block-Feeding Mechanisms for Match Machines, of which the following is a specification.

This invention relates to block feeding mechanism for match machines, our object being to provide simple and efficient means for facilitating and insuring the uniform feeding of a row or rows of blocks along the elongated block-supply trough and into engagement with the feed-rolls by means of which the blocks are positively advanced to the path of the splint cutting instrumentalities of the match machine.

The invention, in its preferred embodiment herein illustrated, comprises an endless conveyer having its upper or active run extending into and longitudinally of the bottom of the block-supply trough; a vertically-movable frame overhanging the trough and said conveyer in advance of the feed-rolls and equipped with pressure and feed devices including an endless conveyer whereof the active run bears yieldingly upon and longitudinally of the blocks within the trough when the frame is in down position, and means whereby the said conveyers are concurrently driven in such a manner that the active runs thereof are caused to travel toward the feed-rolls.

The invention also comprises novel features of construction and combinations of parts, all of which will be hereinafter described and claimed.

In the drawings—

Figure 1 is a plan of a portion of the block-supply trough and associated parts equipped with block-feeding mechanism embodying the principle of our invention.

Fig. 2 is a vertical section of the block guide structure which leads to the cutting mechanism of the match machine; the feed rolls in said structure, and the adjacent end of the trough, as on the line 2—2 of Fig. 1.

Fig. 3 is a partial side elevation of the guide structure, showing the gearing for the feed rolls.

Fig. 4 is a side elevation of the trough 55 and the block-feed mechanism thereof.

Fig. 5 is a vertical section through said trough and mechanism, as on the line 5—5 of Fig. 4.

Referring to the drawings, 10 designates 60 a portion of a guide structure adapted to receive blocks of wood 11 and direct them to the path of the usual splint cutters of the match machine. Intermittently rotatable feed rolls 12 are arranged in pairs within 65 said structure and are adapted to engage the blocks (11) at top and bottom and advance them positively to the path of the cutters. The shafts or trunnions 13 of the rolls, which have their bearings in the sides of the 70 structure 10, are geared together for concurrent rotation by a train of gears 14 at one side of the structure. One of the shafts or trunnions is provided at the opposite end of the structure with a ratchet wheel 15 and an 75 oscillating lever 16, one arm of the latter carrying a pawl 17 in engagement with the teeth of the ratchet wheel. The other arm of the lever is connected to and operated by a reciprocating link 18 to effect the intermittent 80 rotation of the ratchet wheel and its shaft, such motion being transmitted thence through the gearing to the feed rolls, as usual.

The block supply trough 19 leading to the 85 guide structure is illustrated as provided with two spaced parallel partitions 20 which afford three longitudinal channels whereby three rows of blocks are directed simultaneously to the guide structure, but, of 90 course, a trough constructed to support and supply a less or greater number of rows of blocks may be employed, if desired.

Arranged in and longitudinally of the bottoms of the respective channels are means 95 for engaging the bottoms of the blocks and impelling them toward the delivery end of the trough, i. e., toward the feed rolls. In the present instance such means comprises a series of endless conveyer chains 21 which 100 are supported in spaced relation to each other on sprocket wheels 22, 23 located beneath and adjacent the respective ends of the trough. The shafts 24, 25 for the sprocket wheels have their bearings in depending brackets 26 affixed to the sides of the trough. The upper runs of the chains 105 extend through longitudinal slots 27 in the

bottoms of the respective channels of the trough so as to present extended bearing surfaces medially to the under faces of the blocks contained within the channels. Such 5 upper runs preferably rest upon suitably-disposed rails 28 which are supported at intervals by cross-bars 29 beneath the trough. These bars are preferably secured to side brackets 30 on the trough by vertical 10 set-screws 31, by the manipulation of which screws the bars together with the rails can be nicely adjusted vertically in order to effect and ensure the proper positioning of the upper runs of the chains in respect to 15 the bottoms of the channels.

Fast on the shaft 24 at the delivery end of the trough is a sprocket wheel 32 about which passes a chain 33 which is driven from a suitable source of power in such a manner 20 as to impel the upper runs of the conveyer chains 21 toward the delivery end of the trough, and thus correspondingly advance the blocks toward the feed rolls.

Overhanging the delivery end of the 25 trough is a vertically-movable frame that can be raised or lowered in respect to the top of the trough, as desired. This frame preferably comprises a pair of spaced side rails 34 which are rigidly united by top 30 cross-bars 35 and are provided at their inner ends with depending brackets 36 having lateral hubs 37. The hubs are loosely hung on a shaft 38 journaled in bearing brackets 39 on a cross bar 40 which is bolted to the 35 top of the guide structure 10, whereby the frame can be bodily swung on the shaft as an axis.

Mounted on the frame is auxiliary impelling means for engaging the tops of 40 the blocks as they approach the delivery end of the trough, which means co-operates with the lower impelling means to advance the blocks progressively into the guide structure and to the bite of the feed rolls. The 45 auxiliary impelling means is preferably of the following construction: Fast on the shaft 38 are sprocket wheels 40, which together with similar wheels 41 mounted on a shaft 42 borne by depending lateral brackets 43 at the opposite end of the frame, support and guide a series of conveyer chains 44 which correspond in number with and 50 overlie the respective channels of the trough.

The lower runs of the chains 44 are maintained in parallelism by channel bars 45 bearing longitudinally thereon, such bars being 55 yieldingly depressed by springs 46 which are interposed between the respective bars 45 and overlying cross-members 47 carried by the frame. These cross-members 60 comprise bars having up-standing end portions which are bolted to the respective sides 34 of the frame. Above each of the cross-members 47 is a similar member 48 the two 65 members being suitably perforated for the

free passage of a vertical guide stem 49 rising from the underlying channel bar 45. Preferably each of the bars is depressed by two spaced-apart springs 46 and hence two sets of cross-members are provided.

On one end of the shaft 38 is a sprocket wheel 50 with which engages the drive chain 33 above referred to. Thus the wheel 50, its shaft 38 and the conveyer chains 44 are driven concurrently with the conveyer chains 21 in the bottom of the trough, the lower or active runs of the chains 44 travelling in the same direction as the upper runs of the chains 21, that is, toward the feed rolls.

By the construction and co-operative arrangement of mechanism above described it will be seen that when the swinging frame is in down position, as shown by the full lines in Fig. 4, the chains 44 bear yieldingly upon and longitudinally of the tops of the blocks as the latter approach the delivery end of the supply trough, and hence such chains, in conjunction with the underlying chains 21, firmly grip the advancing blocks 90 and feed them positively into the guide structure and to the bite of the feed rolls, which rolls at once grip the entering blocks and advance them step-by-step to the reciprocating cutters of the match machine. It will also be seen that access to the leading blocks or to the interior of the forward end of the supply trough can be readily had, as occasion may require, by merely swinging the frame upward on its axis, as indicated 100 by the dotted lines in Fig. 4.

It is to be understood that our invention is not limited to the details of construction herein disclosed, as the mechanism may be modified within the principle of the invention and the scope of the appended claims.

We claim—

1. In block feeding mechanism for match machines, the combination with block-feed rolls, supporting and operating elements therefor, and a block-supply trough leading to said rolls, of block-impelling means including an endless conveyer having its active run extending longitudinally of the bottom of the trough, a vertically-movable frame overhanging the trough in advance of said rolls, other block-impelling means including an endless conveyer mounted on said frame and having its active run extending longitudinally of the trough, means for yieldingly pressing the latter conveyer against the blocks when the frame is in down position, and means for concurrently actuating the said conveyers to impel their active runs in a direction toward the feed rolls.

2. In block feeding mechanism for match machines, the combination of block-feed rolls, supporting and operating elements therefor, and a block-supply trough leading

- to said rolls, said trough having a longitudinally slotted bottom, of block-impelling means including an endless conveyer having its active run extending along the 5 slot in said bottom, a rail supporting said run, means for vertically adjusting said rail, a vertically-movable frame overhanging the trough in advance of said rolls, other block-impelling means including an 10 endless conveyer mounted on said frame and having its active run extending longitudinally of the trough, means for yieldingly pressing the latter conveyer against the block when the frame is in down position, 15 and means for concurrently actuating the said conveyers to impel their active runs toward the feed rolls.
3. In block feeding mechanism for match machines, the combination of block-feed 20 rolls, supporting and operating elements therefor, and a block-supply trough leading to said rolls, of means including an element for engaging the bottoms of the blocks and impelling them along the trough and 25 toward the feed rolls, a swinging frame overhanging the trough in advance of the feed-rolls, block-impelling means including an endless conveyer chain mounted on said
- frame and having its active run extending longitudinally of the trough, yielding pressure means for said active run, and means for actuating said chain concurrently with the element for engaging the bottoms of the blocks. 30
4. In block feeding mechanism for match 35 machines, the combination with block-feed rolls, supporting and operating elements therefor, and a block-supply trough leading to said rolls, means including an element for engaging the bottoms of the blocks and 40 feeding them along the trough and toward the feed-rolls, a swinging frame overhanging the trough in advance of the feed-rolls, sprocket wheels carried by said frame, an endless conveyer chain mounted on said 45 wheels and having its active run extending longitudinally of the trough, a pressure bar extending longitudinally of and resting on said active run, springs arranged to bear upon and depress said bar, and means for 50 actuating said chain concurrently with the element for engaging the bottoms of the blocks.

WILLIAM J. ELDER.
EDGAR A. ALLEN.
